REFRIGERATOR LOCK

Lloyd Anderson, Rockford, Ill., assignor to National Lock Co., Rockford, Ill., a corporation of Delaware

Application September 4, 1934, Serial No. 742,571

3 Claims. (Cl. 292—166)

This invention relates to a locking means appropriate for a domestic refrigerator; it being understood however that the use of the invention is not intended to be restricted solely to refrigerators, since the locking means herein described may be applied to various structures other than refrigerators.

Among other objects the invention is intended to provide an improved locking contrivance appropriate for a domestic refrigerator and of such character that the locking and unlocking of the refrigerator door can be accomplished very conveniently and without necessitating the use of a person's hand for manipulation of locking a lock-releasing means. Other objects are to be provide a locking contrivance of such character that the lock mechanism is concealed; and to provide an arrangement whereby the refrigerator door when opened is free of any objectionable projecting lock bolt or the like. Further objects are to provide an improved lock mechanism of a type adapted for automatic locking and operable to a release position; and to provide improved means operable for actuating the lock mechanism to release position. A further object is to provide a locking contrivance the mechanism and parts of which shall be of practicable and reliable character from the standpoint of mechanical construction.

The invention will be described by reference to an illustrative embodiment thereof shown in the accompanying drawings, and will be particularly pointed out and defined in the claims following the description.

In said drawings:

Fig. 1 is a front elevation of a refrigerator embodying the invention.

Fig. 2 is a horizontal section taken through a front corner portion of the refrigerator (on the line 2—2 of Fig. 7), this view showing the refrigerator door closed and locked.

Fig. 3 is a view similar to Fig. 2 showing the lock mechanism in release position.

Fig. 4 is an end view of the lock housing and lock bolt.

Fig. 5 is a vertical sectional elevation taken through the door jamb on the line 5—5 of Fig. 6.

Fig. 6 is a section on the line 6—6 of Fig. 5.

Fig. 7 is a side elevation of the lock mechanism looking at the rear side thereof, but omitting the means associated with said mechanism for actuating it from a foot lever.

Fig. 8 is a horizontal section taken on the line 8—8 of Fig. 5.

Fig. 9 is a horizontal section taken on the line 9—9 of Fig. 5.

Fig. 10 is a top plan view of the lock bolt.

Fig. 11 is a sectional view of said lock bolt.

Fig. 12 is a detail view of a lever operative to retract the lock bolt.

Fig. 13 is a rear side view of the lock mechanism with the means associated therewith whereby to actuate the same from a pedal or foot lever.

Fig. 14 is an end elevation of Fig. 13, looking 10 at the end opposite from that from which the lock bolt protrudes.

Fig. 15 is a plan view of the foot lever.

Fig. 16 is a side elevation of said foot lever.

In the drawings, the numeral 1 designates a refrigerator cabinet having a door 2 which swings on the hinges 3. As shown in Fig. 2, the door in its closed position is locked by a concealed lock mechanism the lock bolt 7 of which normally projects from the door jamb 4 through the jamb 20 face plate 5 into engagement with the door catch or keeper 8. The door is equipped with a striker 9. In the movement of the door to closed position, the striker 9 coacting with the lock bolt forces it backward against the resistance of its 25 spring 6, and, when the door reaches the fully closed position, the spring actuated lock bolt snaps into engagement with the door catch, thus automatically locking the door.

As shown in Fig. 1, the door is entirely free of 30 exposed lock fittings. Moreover the lock mechanism is mounted in the corner member of the refrigerator cabinet structure which constitutes the door jamb, so that the door when open is free of any projecting lock bolt or the like that might 35 catch in a person's clothing.

Mounted exteriorly of the refrigerator is a push bar 10, which is preferably arranged beside the door and vertically disposed and of such length that it can be conveniently actuated by a 40 pressure of the arm, wrist, elbow, shoulder, back, hip or knee. A slight pressure against this push bar will cause the lock mechanism to be actuated from the position shown in Fig. 2 to the position shown in Fig. 3, thereby retracting the catch bolt 45 and releasing the door for opening. Any suitable means may be provided to cause the door to open when it is unlocked. For example the rubber sealing strip 11, which is compressed between the door and front side of the cabinet when the 50 door is closed, will exert a sufficient reaction to push the door outward when it is unlocked. Or the door when released may be opened by spring means embodied in the door hinges, or by other appropriate means.

As shown in Figs. 5, 6, 8 and 9, the push bar 10 is rigidly attached to and carried by a pair of parallel horizontal rods 12 and 13 which are arranged one a substantial distance above the other and are guided for reciprocatory motion in the door jamb. Said rods 12 and 13 are pivotally connected to lever arms 14 and 15 respectively which are rigidly attached to and project from a vertical rod 16 pivotally mounted in the door jamb. Inasmuch as the push bar 10 and rod 16 are parallel, and connected through the parallel rods 12 and 13 and the equal lever connections 14 and 15, the movement of the push bar 10 will always be in parallelism with itself. Normally the push bar is in the position shown in Figs. 6 and 8. For actuating the lock mechanism to release the door, the push bar is pushed inwardly to the position shown in Fig. 9. The means by which this movement of the push bar accomplishes the release actuation of the lock mechanism will be hereinafter described. Small springs 17 reacting between the rods 12, 13 and lever arms 14, 15 assist in maintaining the push bar in its normal outward position.

The vertical rod 16 is shown having its upper end mounted in a bracket 18, while its lower end has a hole receiving a pintle 19 projecting from the housing 20 which contains the lock mechanism (Figs. 4, 5, 6 and 7). The door jamb is recessed at 21 to receive the bracket 18 and upper lever arm 14, and is recessed at 22 to receive the lock housing and lower lever arm 15. The jamb is also longitudinally recessed at 23 to accommodate the vertical rod 16.

As shown in Fig. 5, the push bar 10 may be constructed as a corrugated sheet metal tube having a top plug 24, a bottom plug 25 into which is screwed the reduced threaded end or screw extension 26 of the rod 13, and having an intermediate plug 27 into which is screwed the similar screw extension 28 of the rod 12. By this construction, the connections of the push bar to its carrying rods are concealed, and there are no screws in the bar handle to become loosened with long wear and service.

By virtue of the parallelism of the push bar 10 and pivot rod 16, and the equalized connections between said push bar and rod provided by the upper connections 12, 14 and lower connections 13, 15, the long push bar can be operated to effect the unlocking of the door by pushing against the push bar at any point, or against either its upper or lower part; and, as will be apparent, it may be conveniently operated by pushing against it either with the hand or with the elbow, knee, shoulder or hip, or other part of the body of the person who desires to obtain access to the refrigerator. Only a light push against the push bar is necessary to cause the unlocking of the door.

The lock mechanism, shown more clearly in Figs. 2, 3, 4 and 7, comprises the spring actuated lock bolt 1 and a lever 30 which is connected with the lock bolt by the link 31. The lock bolt is separately shown in Figs. 10 and 11. In the form shown, the lock bolt comprises a head and a pair of spaced arms 32 and 33 extending therefrom, said arms being rigidly secured to the lock bolt head by the rivet 34 and short rivets 35. The link 31 is pivotally connected with the lock bolt head through the rivet 34. The lock bolt is guided for rectilinear movement in the lock housing, being so guided between a wall of the housing and a guide roller 36, and also by means of the fixed pivot post 37 which extends through lon-

gitudinal guide slots 38 in the arms 32 and 33 of the lock bolt. The lever 30 is shown in detail in Fig. 12. In the form shown it comprises a pair of spaced parallel lever arms joined by the central connecting post 39. Said lever is pivoted on the stud or post 40, and carries a stud or post 40 by which the link 31 is pivotally connected with the lever. The upper arm 32 of the lock bolt has a lateral cutaway portion or recess 41 through which the stud or post 40 extends. This construction permits the lever 30 to be moved from the position shown in Fig. 2, to the position shown in Fig. 3, in which movement the stud or post 40 carried by said lever travels in the cutaway part or recess 41. The lower arm of the lock bolt 15 may be similarly formed so that both arms can be made with the same die. Said movement of the lever 30 from the position shown in Fig. 2 to the position shown in Fig. 3 shortens the distance between 37 and 40, thereby retracting the lock bolt from door locking position. In this movement there is substantially no resistance by the lock bolt actuating spring 6, because said spring encircling the link 31 acts between the pivot stud 40 and the abutment 43 formed on 25 the link. Thus in the movement of the lever the link 31, spring 6 and abutments of said spring move as a unit, so that substantially no increased tension is imposed on the spring. Lever 30 is normally held in the position shown in Fig. 2 by the spring 43, shown as a coiled spring arranged around the pivot post 37 and reacting between the lock housing and lever.

For actuating the lever 30, the lower push bar carrying rod 13 is provided with a rigid arm 44 arranged to engage the stud 40 which projects through an arcuate slot 45 in the top of the lock housing. The normal position of the push bar relative to said stud 40 is shown in Fig. 8. When the push bar is pushed inwardly, as shown in Fig. 9, the arm 44 coacting with the stud 40 pushes it to the position shown in said Fig. 9, thereby actuating the lever 30 and lock bolt to the release position shown in Fig. 3. As soon as pressure on the lock bar is released, the spring 43 returns the lock mechanism to the normal position shown in Figs. 2 and 7. Such action of the spring 43 assists to return the push bar to the normal position shown in Fig. 8, since the post 40 bears against the arm 44 attached to the push bar. 50 The previously mentioned springs 17 also assist in returning the push bar to normal position. When the lock mechanism is in normal position, the lock bolt can be displaced by the door striker 1, as the door is moved to closed position, 55 such displacement of the lock bolt against the resistance of its spring 6 being allowed by the longitudinal slot 46 in the link 31.

An additional means is provided whereby the lock mechanism can be actuated to release the door by depressing a conveniently located pedal or foot lever. The mechanism for this purpose is shown more clearly in Figs. 13 to 16. As shown a bell crank lever 47 is pivoted at 48 to a rigid support 49 shown as a projecting part of the lock housing. Said bell crank lever is adapted to be actuated by the pull rod or wire 50 which passes vertically through the lock housing and through the arm 51 of the bell crank lever. A spring 52 acting between the lock housing and the arm 51 holds the bell crank lever in the normal position shown in Fig. 13. The wire or rod 50 has at its upper end a head 53, between which and the arm 51 is a cushioning spring 54. By a downward pull on the rod or wire 50, the bell crank lever is ac- 75

tuated in a counterclockwise direction (looking at Fig. 13) so that a projection 56 on the bell crank lever arm 55 will engage the post 39 of the lever 30 and thereby actuate said lever to the 5 position shown in Fig. 3. Thus the lever 30, the pivot stud 37 of which is between the member 39 and swinging stud 40, can be actuated either by a push on the stud 40 in one direction, as already explained, or by a push on the member 39 10 in the opposite direction, accomplished by a downward pull of the rod or wire 50.

The pull rod or wire 50 is connected at its lower end to a foot lever 57. As shown in Figs. 15 and 16, the foot lever is fulcrumed to a support 15 58 mounted in one of the refrigerator supporting legs 59. A spring 60 presses the foot lever downward, thereby maintaining an appropriate tension on the pull rod or wire. The spring 52 is stronger than the spring 60, so that the foot 20 lever must be depressed against the resistance of spring 52 in order to actuate the bell crank lever 47.

An adjustable connection between the pull rod or wire and the foot lever is provided by forming the lower end of the rod or wire with a 25 screw portion which screws into the member 61 having a ball-shaped extremity 62 engaging the under side of a socket-shaped part 63 of the pressed steel foot lever. A lock nut 64 preserves 30 the adjustment. Said ball-shaped member 62 is adapted to be engaged with the socket-shaped part 63 of the foot lever by inserting said ball member through the enlarged end 65 of a slot 66 and then moving the ball member into engagement with the socket-shaped part of the 35 foot lever.

From the foregoing, it will be seen that the invention provides a locking contrivance of highly practicable, convenient and reliable character, 40 whereby the locking of the refrigerator is automatically accomplished when the refrigerator door is slammed or pushed to closing position, and whereby access to the refrigerator can be readily obtained without requiring the use of 45 either hand for manipulating locking or lock-releasing means. A refrigerator equipped with the invention in the form herein illustrated is exceedingly convenient for the housewife who, while having both hands occupied in handling 50 food or dishes, can cause the door to unlock and open by pressing against the push bar 10 with her arm or elbow, or with the back of the wrist; and who, after placing articles into and taking other articles out of the refrigerator, can close the 55 door with a movement of the foot or knee, with the effect of automatically locking it. The foot lever operated means in association with the lock mechanism affords a further convenience, in enabling the door to be opened by a pressure of 60 the foot on the pedal. The invention contributes to pleasing appearance of the refrigerator by absence of exposed lock fittings, and has other advantages hereinbefore indicated.

It will be understood that various changes in 65 the details of construction and arrangement may

be made without departure from the spirit of the invention.

What I claim as my invention, and desire to secure by Letters Patent, is:

1. In combination with a swinging door and a door jamb, a push bar disposed longitudinally of the door jamb adjacent to the swinging end of the door, parallel rods rigidly attached to and projecting from said push bar and slidably mounted in the jamb, a rod parallel with said push bar and pivotally mounted in the jamb, equal connections between said push bar carrying rods and said rod which is parallel with the push bar, whereby a push against the push bar at any point along its length will cause the push bar to move in parallelism with itself, a door locking mechanism mounted in the door jamb, said mechanism having a normally protruding spring-actuated lock, said mechanism including spring-held means associated with the lock bolt and displaceable to retract the lock bolt from locking position, and means operable by the push bar for so displacing said means to retract the lock bolt. 25

2. The combination with a door jamb, of a latch mechanism including a spring projected latch bolt, mounted in said jamb, a vertically disposed rod rotatably mounted in said jamb, means operable by rotative movement of said rod for retracting said bolt, a plurality of arms fixed to and projecting laterally in spaced apart relation from said rod, a plurality of rods slidably mounted in spaced relation in said jamb, the inner end of each of said rods being pivotally connected with the free end of a corresponding one of said arms and the outer end thereof projecting outwardly beyond the face of said jamb, and a push bar disposed parallel with said rotatable rod and fixed to and carried by the projecting ends of said slide rods, whereby pressure applied to said push bar will actuate said rotatable rod to retract said bolt. 35

3. The combination with a door jamb, of a latch mechanism including a casing mounted in said jamb and a spring projected latch bolt extending from said casing, a rod rotatably mounted in said jamb with one end disposed in proximity to said casing, means operable by rotative movement of said rod for retracting said bolt, a plurality of arms projecting in parallelism from said rod and spaced apart longitudinally thereof, a plurality of rods reciprocably mounted in said jamb in cooperative relation with said arms, the inner end of each of said reciprocable rods being 50 pivotally connected with its corresponding arm and the outer end thereof projecting outwardly beyond the face of said jamb, and a push bar secured to and carried by the outer ends of said reciprocable rods so as to be capable of movement toward and from said jamb, movement of said bar toward said jamb acting through said reciprocable rods, said arms and rotatable rod to retract said latch bolt. 55

LLOYD ANDERSON.
